US0D1012180S

(12) **United States Design Patent** (10) **Patent No.:** **US D1,012,180 S**
(45) **Date of Patent:** **** Jan. 23, 2024**

(54) **LOW PROFILE PUSHBUTTON**

(71) Applicant: **Aristocrat Technologies Australia Pty Limited**, North Ryde (AU)

(72) Inventor: **Rajendrasinh Jadeja**, Las Vegas, NV (US)

(73) Assignee: **ARISTOCRAT TECHNOLOGIES AUSTRALIA PTY LIMITED**, North Ryde (AU)

(**) Term: **15 Years**

(21) Appl. No.: **29/698,512**

(22) Filed: **Jul. 17, 2019**

(51) LOC (14) Cl. **21-03**

(52) U.S. Cl.

USPC **D21/333; D21/369**

(57) **CLAIM**

The ornamental design for a low profile pushbutton, as shown and described.

DESCRIPTION

FIG. 1 is a top perspective view of a low profile pushbutton showing my new design according to a first embodiment;

FIG. 2 is a top plan view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top perspective view of a low profile pushbutton showing my new design according to a second embodiment;

FIG. 8 is a top plan view thereof;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top perspective view of a low profile pushbutton showing my new design according to a third embodiment;

FIG. 14 is a top plan view thereof;

FIG. 15 is a front elevation view thereof;

FIG. 16 is a rear elevation view thereof;

FIG. 17 is a right side elevation view thereof;

FIG. 18 is a left side elevation view thereof;

FIG. 19 is a top perspective view of a low profile pushbutton showing my new design according to a fourth embodiment;

FIG. 20 is a top plan view thereof;

FIG. 21 is a front elevation view thereof;

FIG. 22 is a rear elevation view thereof;

FIG. 23 is a right side elevation view thereof; and,

FIG. 24 is a left side elevation view thereof.

The dashed broken lines in the figures illustrate portions of the low profile pushbutton that form no part of the claimed design.

1 Claim, 12 Drawing Sheets
